US0D1004658S

(12) **United States Design Patent** (10) **Patent No.:** **US D1,004,658 S**
(45) **Date of Patent:** **** Nov. 14, 2023**

(54) **GREASE FITTING CLEANING TOOL**

(71) Applicant: **Lijiang Sun**, Hangzhou (CN)

(72) Inventor: **Lijiang Sun**, Hangzhou (CN)

(**) Term: **15 Years**

(21) Appl. No.: **29/893,110**

(22) Filed: **May 25, 2023**

(30) **Foreign Application Priority Data**

May 6, 2023 (CN) 202330259958.2

(51) **LOC (14) Cl.** **09-09**

(52) **U.S. Cl.**

USPC **D15/150**

(58) **Field of Classification Search**

(57) **CLAIM**

The ornamental design for a grease fitting cleaning tool, as shown and described.

DESCRIPTION

FIG. 1 is a front, right and top perspective view of a grease fitting cleaning tool, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the grease fitting cleaning tool that form no part of the claimed design.

1 Claim, 8 Drawing Sheets
